UNITED STATES PATENT OFFICE.

BONIFACE A. GRASBERGER, OF RICHMOND, VIRGINIA.

COAT-HANGER.

No. 890,271.

Specification of Letters Patent.

Patented June 9, 1908.

Application filed January 25, 1908. Serial No. 412,672.

To all whom it may concern:

Be it known that I, BONIFACE A. GRASBERGER, citizen of the United States, residing at Richmond, in the county of Henrico and State of Virginia, have invented certain new and useful Improvements in Coat-Hangers, of which the following is a specification.

The present invention relates to apparel apparatus and more particularly to an improved coat hanger which is peculiarly constructed so as to automatically accommodate itself to any shape of coat, whether round or square shouldered so as to permit the coat to hang without wrinkles.

15 The object of the invention is to design a coat hanger of this character which is simple and inexpensive in its construction and can be utilized in the ordinary manner.

For a full description of the invention and 20 the merits thereof and also to acquire a knowledge of the details of construction and the means for effecting the result, reference is to be had to the following description and accompanying drawings, in which:

25 Figure 1 is a side elevation of a coat hanger embodying the invention. Fig. 3 is a bottom plan view of the same portions being removed; Fig. 3 is a sectional view on the line 3—3 of Fig. 1. Fig. 4 is a sectional view 30 through a portion of a coat hanger showing a modification.

Corresponding and like parts are referred to in the following description and indicated in all the views of the drawings by the same 35 reference characters.

Broadly speaking the coat or garment hanger comprises a supporting frame having shoulder pieces loosely mounted thereon so as to automatically accommodate themselves 40 to the particular coat or garment placed upon the hanger. In the preferred embodiment of the invention the supporting frame is in the nature of a transverse bar 1 the opposite ends of which slope downwardly from 45 the central portion of the bar, a suspending hook 2 being provided which projects upwardly from the bar. A shoulder piece 3 is movably mounted upon each end of the bar 1, the said shoulder pieces being designed 50 to swing both laterally and vertically. As shown in the present instance each of the shoulder pieces 3 is provided at an intermediate point with a recess 4 receiving the cross bar of a U-shaped clip 5 which is pivoted 55 within the recess, the width of the recess being greater than that of the cross bar to

permit a lateral swinging movement of the shoulder piece and the said swinging movement being limited by the shoulders at opposite ends of the recess. Each of these clips 5 is pivotally connected to an end of the bar 1 by means of a pin 7 passing through a selected one of a series of openings 8, the said clips permitting the shoulder pieces to swing in a vertical plane and also enabling the same 65 to be moved toward or away from each other so as to accommodate both large and small coats. It will thus be apparent that both of the shoulder pieces are adapted to swing laterally about their pivotal connection with the clips 5 and also in connection 70 with the said clips to swing vertically.

When a coat or other garment is placed upon the hanger the shoulder pieces 3 automatically adjust themselves to the particular form of the coat and permit the same to hang without wrinkles. It may also be found desirable under some conditions to provide the bar 1 with hooks 6 for engaging the buttons of a pair of trousers, although 80 this is entirely optional with the person using the invention. While I have described a specific embodiment of the invention in which the shoulder pieces are connected to the bar by means of clips, it is to be understood 85 that I do not limit myself to such a construction since it is clearly within the spirit of the invention to employ any equivalent means for mounting the shoulder pieces so that they will be enabled to automatically 90 adjust themselves to the coat in the manner described.

A modification of the invention is shown in Fig. 4 in which the numeral 1^a designates a portion of the supporting frame and 3^a a portion of the shoulder-piece. Projecting downwardly from an intermediate portion of the shoulder-piece 3^a is a lug 9 bearing against the supporting frame 1^a and adapted to rock upon the same. A screw 10 is threaded within this lug 9 and projects downwardly through an opening 11 in the supporting frame, the said opening being flared downwardly to permit the lower portion of the screw to have a swinging movement within the opening as the shoulder-piece rocks upon the frame. In the present instance a washer 12 is applied to the screw 10 and bears loosely against the lower face 100 of the supporting frame 1^a so as to prevent the head of the screw from being drawn upwardly into the flared end of the opening 11.

This manner of connecting the shoulder-pieces to the supporting frame entirely eliminates any intermediate member such as the clip 5 and at the same time permits the 5 shoulder-piece to swing both laterally and vertically so as to readily accommodate itself to any shape of coat.

Having thus described the invention, what is claimed as new is:

10. 1. A garment hanger comprising a transverse bar, and a shoulder-piece mounted upon each end of the bar, the said shoulder-pieces being adapted to swing about two axes at right angles to each other.
15. 2. A garment hanger comprising a supporting frame and shoulder pieces adjustable

upon the frame so as to be moved toward or away from each other, the said shoulder pieces being mounted to swing about two axes at angles to each other.

- 20
3. In a garment hanger, the combination of a supporting frame, clips pivotally connected to the frame, and a shoulder-piece pivotally mounted upon each of the clips to swing about an axis at right angles to that of 25 the clip.

In testimony whereof I affix my signature in presence of two witnesses.

BONIFACE A. GRASBERGER. [L. S.]
